DESIGN FOR AN OUTBOARD MOTOR FOR BOATS

Owen C. Linthwaite, South Bend, Ind.

Application July 27, 1936, Serial No. 64,085

Term of patent 14 years

To all whom it may concern:

Be it known that I, Owen C. Linthwaite, a citizen of the United States, residing in South Bend, in the county of St. Joseph and State of Indiana, have invented a new, original, and ornamental Design for an Outboard Motor for Boats, of which the following is a specification, reference being had to the accompanying drawing, forming part thereof.

In the drawing:

Figure 1 is a side elevation of an outboard motor for boats embodying the invention;

Figure 2 is a rear elevation thereof; and
Figure 3 is a top view of same.

I claim:

The ornamental design for an outboard motor for boats as shown.

In testimony whereof, I have hereunto signed my name.

OWEN C. LINTHWAITE.
